DESIGN FOR A STATUETTE

Donald Oliver Crandall, Minneapolis, Minn., assignor of one-half to Eleanor N. Poehler, Minneapolis, Minn., doing business under name of The Guild

Application May 22, 1939, Serial No. 85,135

Term of patent 7 years

To all whom it may concern:

Be it known that I, Donald Oliver Crandall, a citizen of the United States and residing in the city of Minneapolis, county of Hennepin, and State of Minnesota, have invented a new, original, and ornamental Design for a Statuette, of which the following is a specification, reference being had to the accompanying drawing, forming a part thereof, wherein,

Fig. 1 is a view in front elevation illustrating a statuette showing my new design;

Fig. 2 is a view in side elevation of the same;

Fig. 3 is a view in rear elevation of the same; and

Fig. 4 is an enlarged cross section through one of the wings of the statuette taken substantially on the line 4-4 of Fig. 1 as indicated by the arrows.

I claim:

The ornamental design for a statuette, substantially as shown.

DONALD OLIVER CRANDALL.
